TIMING LIGHT

Edwin L. Schwartz, 16604 Park Lane Place,
Los Angeles, Calif. 90049

Filed Sept. 26, 1969, Ser. No. 19,310

Term of patent 14 years

Int. Cl. D26—04

U.S. Cl. D52—1

Fig. 1

Fig. 1

FIG. 1 is a perspective of the timing light, showing my new design;

FIG. 2 is a side elevational view taken from the back of FIGURE 1;

FIG. 3 is a bottom plan view taken from the bottom of FIGURE 2;

FIG. 4 is an end elevational view taken from the right side of FIGURE 2; and

FIG. 5 is an end elevational view taken from the left side of FIGURE 2.

I claim:

The ornamental design for a timing light, substantially as shown.
